DESIGN FOR A DRESS OR SIMILAR ARTICLE

Lillie B. Starr, New York, and Samuel E. Badanes,
Flushing, N. Y.

Application April 11, 1939, Serial No. 84,200

Term of patent 3½ years

To all whom it may concern:

Be it known that we, Lillie B. Starr, a citizen of the United States of America and resident of the city of New York, county of New York, and State of New York, and Samuel E. Badanes, a citizen of the United States of America and resident of Flushing, in the county of Queens and State of New York, have invented a new, original, and ornamental Design for a Dress or Similar Article, of which the following is a specification, reference being had to the accompanying drawing, forming part thereof:

We claim:

The ornamental design for a dress or similar article, as shown.

LILLIE B. STARR.
SAMUEL E. BADANES.
